OF NEW YORK, N. Y., A CORPORATION OF NEW YORK.

FLEXIBLE-SHAFT CONNECTION.

1,279,773.

Specification of Letters Patent. Patented Sept. 24, 1918.

Application filed August 25, 1917. Serial No. 188,137.

To all whom it may concern:

Be it known that I, OSCAR SPERLING, a citizen of Sweden, and a resident of the borough of Manhattan, in the county, city, 5 and State of New York, have invented certain new and useful Improvements in Flexible-Shaft Connections, of which the following is a specification.

This invention relates generally to shaft- 10 couplings, and it more especially appertains to means of attachment for the opposite extremities of a flexible shaft, whereby the latter can be connected with a source of power at one end, and coupled with a rotary 15 implement at the other end.

One of the objects of the invention is to produce an improved attachment of the character described enabling a flexible shaft to be readily coupled or uncoupled by any 20 person of ordinary intellect, even though inexperienced, without the use of tools, in a minimum of time, and with the least possible labor.

Another object is the production of coupling members of the type set forth which shall afford to the flexible shaft full protection against either dirt or injury, as well 25 as form an appropriate reservoir for lubricant, such as will prevent any excess thereof 30 from escaping, and thus will serve to keep the handles for the shaft always clean and dry for manipulation.

A further object is to provide a coupling of the class referred to wherein all the members 35 are concentric and of nearly uniform dimensions, differing but slightly in size exteriorly, so that they can be easily handled and will offer little obstruction when moved in close quarters.

40 Still another object is the provision of a coupling of the nature mentioned having a tool-holding socket permanently maintained in rotative balance with a negligible amount of friction and vibration.

45 A still further object is to devise a coupling construction of the kind specified which shall be simple, effective, strong, durable, easily disassembled either for repairs or for replacement of worn-out elements, and amenable to low cost of production.

Other objects and advantages will become apparent as the specification proceeds.

With the aforesaid objects in view, the 55 invention consists of the improvements,

novel construction, arrangements and combinations of parts hereinafter described, defined in the subjoined claims, and illustrated in their preferred embodiments by the annexed drawings, wherein like elements are 60 designated by the same reference numerals throughout the several views.

In the said drawings:

Figure I is a sectional elevation of a coupling member and shaft sleeve pertaining to 65 the power-receiving end of a flexible shaft equipped in accordance with the invention;

Figs. II and III are transverse sections, respectively taken on the lines II—II and 70 III—III of Fig. I, viewed in the direction of the arrows in each instance;

Fig. IV is a sectional elevation showing a tool socket and coupling member at the power delivery end of the said flexible shaft; and 75

Figs. V, VI, and VII are all cross-sections, severally taken from the lines V—V, VI—VI, and VII—VII of Fig. IV, looking toward the right in the first two instances and toward the left in the third case, as 80 pointed out by the three pairs of arrows in the view last named.

Generally described, the invention comprises a rotatable flexible shaft, with a relatively stationary conduit therearound, having coupling members respectively adapted to connect the same with a source of power and a revolvable implement at the opposite ends. The coupling members at the power receiving end include a pair of handle sleeves that are separably joined endwise so as to extend cylindrically over a revolvable element which is operatively connected with a prime mover. Similarly, the coupling members at the power delivery end comprise 95 a pair of hollow handles separably united and extending cylindrically over a revolvable element having an operative connection with a working tool. The first-named element is coupled up externally of its pair of 100 members with the source of power, while the other element is detachably connected within its members in position to deliver and transmit motion to the tool. The several parts involve screw-threaded connections, lubricating chambers, anti-friction bearings, and various other features of construction hereinafter specified in detail.

The advantages of the invention as here outlined are best realized when all of its 110

features and instrumentalities are combined in one and the same structure, but useful devices may be produced embodying less than the whole.

- 5 Referring first to Figs. I, II and III, the letter A denotes the driving shaft of a prime mover, which may be, for instance, the armature shaft of a portable electric motor (not shown). The outer end of the 10 said shaft is arranged to receive a coupling sleeve 1. Preferably, this sleeve is made to take over the shaft A for about one-half the length of its bore, and is secured thereto by means of a headless set-screw 2, having its point countersunk in the surface of the shaft. A similarly arranged screw 3 holds the sleeve to a shank 4, which constitutes the anchor member of a flexible shaft, presently to be described.
- 15 20 As represented principally in Figs. I and IV, the said flexible shaft may be composed of several helically close-wound wire-coils extending in opposed inclination, one around another, and respectively designated by the reference numerals 5, 5^a, 5^b, 5^c. These wire-coils are contained within a similarly wound, flexible, relatively stationary conduit 6.
- 25 One end of the said conduit 6 is fixed to 30 the interior surface of a recess 7, in a socket member 8, for instance, through the agency of solder, indicated at 9. The member 8 is provided with an internal, annular shoulder 10, and a second recess 11, contiguous 35 thereto, within which is rotatably received a collar 12, preferably made integral with the previously mentioned shank 4 of the flexible shaft. The collar 12 is confined in the recess 11, between the said shoulder 10, 40 and the outer end of a threaded plug 13, formed on a reduced portion of a handle sleeve 14, and received in a correspondingly threaded recess 15, also provided with in the said socket member 8, opposite to the 45 recess 7 first above specified.
- 50 The socket member 8 and the adjoining sleeve 14 which constitute together a pair of separable handles are knurled or otherwise roughened on its external surface, as indicated at 16 and 17 to enable the operator to couple it readily by hand with the socket member 8, that is, without the use of implements of any sort. The shank 4 is centered in this sleeve, so that the flexible 55 shaft section 5 runs free of the annular shoulder 10. An aperture 18 is provided in one side of the member 8 for the introduction of lubricant into the intermediate recess 11, to counteract friction of the wearing 60 surfaces of the collar 12 against the adjacent faces of the shoulder 10 and plug 13. For a like purpose, holes 19 are formed in the corresponding side of the handle sleeve 14 to permit lubrication of the shank 65 4 therein, as well as the contacting portion

of the sleeve 1, which the handle is made to abut endwise.

At the other or opposite end, the conduit 6 is secured, conveniently again by solder, as at 21, in a recess 22, formed at one end 70 of a hollow handle, 23. This handle affords a commodious chamber around the flexible shaft, as at 24, which may be filled with grease, for instance, wherewith the shaft is lubricated so as to prevent chafing between 75 its coils.

The end of the handle 23 remote from the recess 22 is interiorly threaded as shown at 25, to receive an exteriorly threaded plug 26. The latter is formed with an enlarged 80 end 27, also screw-threaded externally and fitting internal threads 28, in a coupling handle 29, which is hollow and a companion to the said handle 23.

A chuck 31, having a socket 32, is located 85 at the opposite end of the handle 29. The socket 32 is directed outward, as indicated in Fig. IV, and may be threaded for the reception of a rotary tool, such for example as a buffer (not shown). It is also flattened 90 on opposite sides to form facets, as 33, whereon to apply a wrench when screwing a tool, like that mentioned, into its position in the chuck.

The said coupling handle 29 is counter-bored at its opposite ends, as at 34 and 35 respectively, adjacent to the said chuck 31 and to the enlarged head 27 of the plug 26. Outer races 36 and 37, for bearing balls, are inserted with a force fit in the counterbores 100 34 and 35; and co-operating inner races 36^a and 37^a are similarly pressed over a spindle 39, which projects inwardly from the chuck 31, centrally through the coupling handle 29, and also traverses the bore of the plug 26, 105 before referred to as threaded in the adjoining end of the hollow handle 23. But, it will be noted, the spindle is not journaled in the plug, merely running loose through its center. Anti-friction balls 36^b and 37^b are 110 placed in the raceways respectively formed between the outer and inner races 36, 36^a, and 37, 37^a, above described. The ball bearings thus formed are prevented from coming out of their respective counterbores 34, 115 35 of the coupling handle by the opposed inner faces of the plug head 27 and of the chuck 31. The space intervening between the raceways constitutes a chamber 40, for lubricant, through which the spindle 39 120 passes. Axial alignment of this spindle is maintained by a collar 41, fastened to the inner end thereof, as by means of a pin 42.

Substantially one-half the said spindle 39 has formed therein a longitudinal recess or keyway 43, which may be of semi-circular or segmental formation, as shown. As an exemplification of construction, the keyway 43 may be produced between an integral portion 39^a of the spindle 39, and a companion 125 130

piece 39^b, held thereto through the medium of interengaging dovetails 39^c and similarly formed recesses 39^a, which prevent lateral displacement of the conjoined parts 5 (shown most clearly in Fig. VII). These parts may be brazed together with hard solder, so as to form a rigid whole. The innermost surface of the said integral portion 39^a is flat, as indicated at 39^e, in the 10 last named figure, and constitutes a drive for a tongue or key 44, of same cross-section as the recess or keyway 43, within which it is received. The tongue 44 extends outwardly from a head 45, in which the power 15 delivery end of the flexible shaft is fastened. Countersunk rivets, as 46 and 47, are employed for securing the tongue 44 and the proximate end of the flexible shaft respectively in the head 45, from the opposite 20 extremities thereof; and solder is applied in addition, so as to fill up all interstices. A slight endwise play is permitted to the tongue 44 within the segmental recess 43, to compensate for the bending of the flexible 25 shaft within the conduit 6.

Oil-holes 48 and 49 are provided in the sides of the hollow handles 23 and 29 respectively, for the injection of the lubricant needed in the chambers 24 and 40. The 30 outer, cylindrical surfaces of the said hollow handles are fluted, knurled, or otherwise roughened, as shown at 50 and 51, to afford a proper grip for the operator's hands, when manipulating or screwing these parts to the 35 plug 26 and head 27 thereof, which hold them in alignment.

While a certain preferred embodiment of this device has been shown and described, it will be understood that changes in the 40 form, arrangements, sizes, proportions and details thereof may be made without departing from the scope of the invention as defined by the appended claims.

Having described my invention what I desire to secure by Letters Patent and claim is:—

1. A rotative flexible shaft having a relatively stationary conduit therearound affixed endwise to pairs of separable handle members, combined with revoluble elements coupled up with the opposite extremities of said shaft and disposed adjacent to the ends of the outer members in said pairs.

2. A flexible shaft combined with a conduit therearound having handle members separably joined in pairs, one pair at each end of said conduit, and elements coupled up with said shaft so as to revolve therewith against the ends of the outer members 50 in said pairs, one element receiving power from a suitable source, and the other element delivering the power transmitted thereto to an implement adapted to be held therein.

3. A flexible shaft with a conduit there-

around affixed endwise to pairs of separable screw-connected handle members, combined with revoluble elements coupled up with said shaft and disposed adjacent to the ends of the outer members in said pairs, one of 70 said elements being coupled externally of its members with a source of power and receiving rotation therefrom, while the other one of said elements is detachably connected within its members to the shaft and delivers 75 motion transmitted thereto to an implement adapted to be held by the last mentioned element and rotatively driven thereby.

4. A flexible shaft combined with a conduit therearound affixed at its ends to pairs 80 of separable handle members, the inner member of one pair thereof having an internal shoulder coacting with a reduced portion provided on the outer member in said pair, one end of said shaft including a collared stem having a bearing in said outer member, with its collar, between said shoulder and said reduced portion, and elements revolvably coupled to said shaft and disposed adjacent to the ends of the outer members 85 in both pairs, one of said elements being secured to said stem and constituting a coupling with a source of power for transmitting motion therefrom through the shaft to an implement adapted to be held in the other 90 one of said elements.

5. A flexible shaft combined with a conduit therearound affixed at its ends to pairs 100 of separable handle members, the inner member of one pair thereof being formed with a threaded recess and an internal shoulder, the outer member in the pair having a threaded reduced portion adapted to be received in said recess, one end of said shaft including a stem with a collar lodged between said shoulder and said reduced portion, and elements revolvably connected with the opposite extremities of said shaft and disposed adjacent to the ends of the outer members in said pairs, one of said elements being fixed to said stem and coupled with a source of power so as to transmit movement therefrom through the shaft to an implement adapted to be rotatively held by the other one of said elements.

6. A flexible shaft combined with a conduit therearound affixed at its end to pairs 115 of separable handle members, the inner member of one pair thereof being formed with a threaded recess and an internal shoulder, the outer member in the pair having a threaded reduced portion adapted to be received in said recess, one end of said shaft including a stem with a collar lodged between said shoulder and said reduced portion, and elements revolvably connected with the opposite extremities of said shaft and disposed adjacent to the ends of the outer members in said pairs, one of said elements 120 comprising a sleeve secured to said stem and 125 comprising a sleeve secured to said stem and 130

constituting a coupling between said shaft and a source of power capable of transmitting motion through the shaft to a rotatable implement adapted to be held by the other one of said elements.

7. A flexible shaft having a conduit therearound affixed at each end to a pair of separable handle members, the inner member in one pair being provided with a threaded 10 socket while the outer member thereof has a threaded plug engaging said socket, a spindle passing through said outer member and its said plug, elements revolubly coupled with said shaft and disposed each adjacent 15 to the ends of the outer member in either pair, one element receiving power from a suitable source, and the other element delivering the power through the shaft to an implement adapted to be held thereby, anti-friction 20 bearings confined between the inside faces of said implement-holding element and said plug, said bearings being interposed between the first-named outer member and said spindle, and a detachable connection joining the latter with the power 25 delivery end of the shaft.

8. A flexible shaft having a conduit therearound affixed at its ends to pairs of separable handle members, revoluble elements 30 coupled up with said shaft and disposed adjacent to the ends of the outer members in said pairs, one element receiving power from a suitable source, while the other element delivers the power to an implement 35 adapted to be held thereby, a spindle extending from said implement-holding element through one of said outer members, a detachable connection joining the shaft to said spindle, anti-friction bearings supporting 40 the latter, and means for maintaining axial alignment of the spindle in the last mentioned outer member.

9. A rotative flexible shaft having a relatively stationary conduit therearound, a 45 pair of separable handle members affixed endwise to said conduit, said members including a socket piece recessed at both ends and intermediately thereof, one terminal of said conduit being secured in the recess at 50 one end of said socket piece, the other one

of the members engaging the recess in the opposite end of the latter, a stem constituting a prolongation of said shaft journaled in the last named member and formed with a collar rotatably received in the intermediate recess, and a coupling joining said stem to a suitable source of power. 55

10. A flexible shaft with a conduit therearound, a pair of separable handle members secured to one terminal of said conduit, an 60 element adapted to hold an implement and having a spindle journaled in the outer one of said members, means with said spindle uniting with said element to maintain both of said parts in axial alinement, and a detachable connection operably joining the spindle with said shaft. 65

11. A flexible shaft with a conduit surrounding the same, a pair of separable handle members at one end of said conduit, the inner member of said pair having sockets at opposite ends with a chamber for lubricant therebetween, said conduit being secured in one of said sockets, the outer member of said pair including anti-friction bearings spaced 75 apart one from the other so as to form between them another lubricating chamber, a spindle journaled in said bearings, a chuck adapted to hold a rotatable implement externally of one of said bearings on the outer 80 end of said spindle, a retainer adjacent to the other bearing engaging the other one of said sockets and serving as a connection between the members, and disconnectible means joining said spindle with said shaft. 85

12. A rotatable flexible shaft and a relatively stationary conduit therearound, combined with a pair of separable handle members, the inner one of said members being affixed to one terminal of said conduit, a rotatable element adapted to hold at one end 90 an implement journaled in the outer one of said members, an internal retainer joining the latter providing a clearance for the other end of said element, a head for said 95 shaft, and a detachable tongue and groove connection between said other end of the element and said head.

OSCAR SPERLING.
